UNITED STATES PATENT OFFICE.

CHRISTOPHER C. BRADLEY, OF SYRACUSE, NEW YORK.

DESIGN FOR AN AXLE.

SPECIFICATION forming part of Design No. 33,381, dated October 16, 1900.

Application filed August 24, 1900. Serial No. 27,959. Term of patent 14 years.

To all whom it may concern:

Be it known that I, CHRISTOPHER C. BRADLEY, a citizen of the United States, residing at Syracuse, in the county of Onondaga and State of New York, have invented and produced a new and original Design for Axles, of which the following is a specification, reference being had to the accompanying drawings, forming a part thereof.

Figure 1 is a side view of a complete axle containing the features of my design. Fig. 2 is a top plan view thereof. Fig. 3 is an end view of the axle enlarged.

As shown in the accompanying drawings, the leading or material feature of my design consists in the form of the outer portion of the axle adjacent to and inside of the journal-bearing, it being formed substantially as shown in the drawings, and in which *a* is that

part of the axle just inside of the shoulder 20 and is provided with an arm *b*, having an enlargement, as shown at *c*, adjacent its outer end, the said arm extending substantially parallel with the general direction of the complete axle. The enlargement *c* is substantially cylindrical in cross-section. 25

Having described my invention, what I claim, and desire to secure by Letters Patent, is—

The design for an axle substantially as 30 herein described and shown.

In witness whereof I have hereunto set my hand this 21st day of August, 1900.

CHRISTOPHER C. BRADLEY.
